ROAD MARKING MACHINE

Ira H. Beaman, Buffalo, N. Y., assignor of one-half to Burnwell Corporation, Buffalo, N. Y., a corporation of New York

Application April 2, 1940, Serial No. 327,487

37 Claims. (Cl. 91—12)

My invention relates in general to road marking machines and in particular to that type of machine which is used for striping state and county highways.

It is well known to those skilled in the art that the pavement of state and county highways is now marked to indicate traffic lanes and the safe path for traffic to follow. It is customary to divide the traffic lanes by marking the pavement with a broken line of predetermined cycle, or with a solid line. It is desirable at some places in the highway to make a broken line on either side of a solid line. Moreover, in some places two solid parallel lines are required. Furthermore, in some instances it is desirable to change from one color paint to another.

The principal object of my invention has been to provide a machine having a plurality of paint nozzles so designed that any one of the above mentioned line combinations may be made.

Another object has been to provide a device of this nature by which the cycle of an intermittent or broken line may be changed at will.

Another object has been to provide a road marker having means whereby the line spacing may be conveniently registered with a previously painted broken or solid line.

Another object has been to provide a road marking machine which shall have movable walls for defining the path of the paint as it is applied to the road, means being provided for bringing into road engaging position only those walls which are to be used at the time.

Another object has been to provide a machine whereby a number of colored paints may be applied to the road.

A further object has been to provide means whereby the change of color may be brought about almost instantaneously by a single control valve.

Another object has been to provide a valve to be used in combination with a number of spray nozzles handling different colored paints whereby the change from one color to another may be quickly made.

My device is provided with suitable cam means for automatically painting a broken line of predetermined cycle.

Another object has been to provide means for rendering inoperative the automatic cam action when it is desired to paint a solid line.

Another object has been to provide a mounting for the paint channel defining walls whereby when either of them strikes a foreign object in

the road it will be momentarily moved out of the way until the object has been passed over.

Furthermore, my device is of such a nature that it may be used in a paint striper of the pushmobile type or drawn behind a truck.

The above objects and advantages have been accomplished by the device shown in the accompanying drawings, of which:

Fig. 1 is a side sectional elevation of my complete machine and is taken on line 1—1 of Fig. 2.

Fig. 2 is a plan view of the device.

Fig. 3 is a fragmentary side sectional elevation showing one of the channel defining walls, taken on line 4—4 of Fig. 2.

Fig. 4 is a fragmentary sectional view taken on line 4—4 of Fig. 1.

Fig. 5 is a diagrammatic view showing a modified form of invention in which two nozzles are used, each for a different colored paint with the 20 coating distributing units, control valves and connections therebetween.

Fig. 6 is a longitudinal, sectional view taken through one of the distributing units.

Fig. 7 is an enlarged, transverse sectional view 25 of the two-color air control valve shown in Fig. 5 and is taken on line 7—7 of the valve in that figure.

Fig. 8 is a transverse sectional view of the same taken on line 8—8 of the same figure.

Fig. 9 is a sectional view of the valve taken on line 9—9 of the same figure.

Fig. 10 is a side view of a painting device of the pushmobile type showing my road marking machine attached thereto.

Fig. 11 is a fragmentary view of the rear end 35 of a truck showing my road marking device being drawn thereby.

My device comprises a frame 15 having side plates 16 and 17 fastened together preferably by 40 means of a wall shaft 20 and link shaft 21. Each of these shafts is stationarily arranged and each is provided at each end with screwthreads for the reception of clamping nuts 22. Located along the upper edge of each of the side plates and 45 extending inwardly therefrom is a reinforcing angle 23 to the forward end of each of which is secured the rear end of a draft wishbone member 24. At the forward end of the wishbone member there is provided a draft sleeve 25 in 50 which is mounted a draft stem 26 which carries at its forward end a part 30 of a spherical socket, the other part 31 of which being arranged in front thereof. These two parts are designed to receive and hold a draft ball 32 in limited universal manner. This ball is carried by a ball

stem 33 which is suitably mounted upon the frame 34 of the pushmobile shown in Fig. 10 or upon a suitable angle member 35 carried at the rear of a truck, as shown in Fig. 11.

Extending laterally of the frame 15 are two supporting ways 40 and 41 which have their ends preferably secured near the forward ends of the supporting angles 23. These ways are interspaced and provide means for adjustably fastening the various parts of the device in place, as herein-after described.

Arranged at the rear of the device is a plurality of paint walls 42, 43, 44 and 45. These walls are carried by the wall shaft 20 and the link shaft 21 and they are connected to these shafts by means of front wall links 46, 50, 51 and 52 and rear wall links 53, 54, 55 and 56. These walls when in road engaging position provide means for defining a paint channel during the painting operation and each of them is formed with an upstanding part 60 and with a shoe 61 at its lower edge. The shoe comes in contact with the pavement and is therefore made of hardened steel. It is detachably secured to the lower edge of the wall by means of screws 62.

The front wall links and the rear wall links carrying the walls are pivotally connected at their lower ends to the walls and have substantially the same distance between pivotal connections so that the walls are lowered and raised to and out of road engaging position in parallelism with the surface of the pavement. The front wall link 46 carrying the wall 45 comprises an actuating part 63 and a free part 64. These parts are connected together by means of a bolt 65. In like manner, the front wall links 50, 51 and 52 each comprise an actuating part 66, 67 and 68, and a free part 57, 58 and 59. Each of the actuating parts 63, 66, 67 and 68 is formed at its upper end, respectively, with a hub 70, 71, 72 and 73, each of which is loosely mounted upon the front link shaft 20. Each of these actuating link parts is of single thickness and is arranged between the interspaced side plates 74 of each of the free parts of the front wall links where it is pivotally united by means of the bolts 65. The outer ends of the plates 74 of the free parts of the link are disposed one on each side of their respective walls and are pivotally connected thereto by means of pivot bolts 75. Each of the actuating parts of the front wall links is provided with an arm 77 which extends in between the side plates 74 of the free parts of the links for a considerable distance beyond the pivot bolt 65 thereof and a suitable stop 78 connects the upper edges of the plates at a point opposite the arm 77 so that when the pivotal connections of the actuating and free parts of each of the front links are brought in alignment, the end 77 will contact with the stop 78 and keep the parts in alignment. The free part of each link consisting of the plates 74 is kept in the position shown in Fig. 1 by means of a centralizing arm 79 which extends forwardly of the link and which is held in the position shown by means of a centralizing spring 81. The upper end of this spring is extended by means of a rod 88 to the spring arm 121 where it is suitably fastened. Due to this arrangement, when the walls are held in their road engaging positions, as shown by the dot-and-dash lines in Fig. 3, either of the walls will be free to rise momentarily when a foreign object is encountered in the road. Such object will first ride along the inclined forward edge of the shoe 61 of the wall, raising the wall and causing the

free part of the wall link to be oscillated about its pivotal connection with the actuating part thereof and upon the connecting pivot bolt 65. This oscillation is against the tension of the centralizing spring 81 and the connected centralizing arm 79. As the foreign object is being passed over, the front end of the wall will swing on the free part of the front link and the rear end thereof will swing on the rear wall link, thus raising the wall in substantial parallelism with the road. When the foreign object has been passed over, the wall will again assume its parallel relation with the pavement. When the centralizing spring and centralizing arm draw the front wall link back to its normal position, the stop 78 will engage with the end 77 of the actuating part of the link, thereby bringing the parts thereof into alignment.

Carried by the hub 70 of the front wall link 46 is an upstanding link arm 76 and carried by the hub 73 of the link 52 is an upstanding arm 80. The hubs 71 and 72 of the front wall links 50 and 51 each have an upstanding link arm 81 and 82, respectively. The link arms 81 and 82 are longer than the link arms 76 and 80 for reasons to be hereinafter described.

Arranged between the front wall links 46 and 50 is a link actuating lever 83 having a hub 84 at its lower end and a pad 85 at its upper end. Likewise, between the front wall links 50 and 51 is a link actuating lever 86 having a hub 90 and a pad 91. In like manner, a link actuating lever 92 is mounted between the front wall links 51 and 52 and is provided at its lower end with a hub 93 and with a pad 94 at its upper end. Each of the link actuating levers 83 and 92 is provided near its lower end with an integral cross bar 95 and 96, respectively. The bar 95 extends across in front of the link arms 76 and 81. The cross bar 96 extends across in front of the link arms 80 and 82. The link actuating lever 86 is provided with a cross arm 100 which is located above the cross bars 95 and 96 of the levers 83 and 92, and this cross bar is of sufficient length to extend across in front of the link arms 81 and 82. Each of the link arms 76, 81, 82 and 80 is provided with a suitable set screw for contact with the cooperating cross bar, whereby the position of the walls in respect to the pavement may be accurately adjusted. This arrangement of parts, as will hereinafter be more fully described, permits the operator, through suitable operating means, to select and bring into road engaging position the desired pair or pairs of walls; thus walls 42 and 43 may be used as a pair. Likewise walls 44 and 45 may be moved to road engaging position as a pair, or walls 43 and 44 may be moved to road engaging position in unison.

Wall actuating cylinders 101, 102 and 103 are provided for the link actuating levers 83, 86 and 92, respectively. These cylinders are carried, respectively, by supporting brackets 104, 105 and 106. Each of these supporting brackets, as shown in Fig. 1, is preferably of angle-iron formation, the horizontal leg 110 thereof being adjustably secured in place to the ways 40 and 41 by means of bolts 111. The downwardly extending leg 112 of each bracket serves to provide means for supporting the connection 113 of each wall cylinder and also acts as a stop for the stop rod 114 of each link actuating lever. This stop rod has one end pivotally secured to the associated link actuating lever and its other end passed through a suitable aperture in the leg 112.

where it is provided with adjusting nuts 115 which engage the outer surfaces of the leg when the selected link actuating lever is moved to lower the walls to their operative positions. Each of the cylinders is provided with a plunger 116 which is actuated by air under pressure conducted to the cylinder through its connection 113, to be hereinafter described. When the plunger 116 is forced outwardly it causes the respective link actuating lever to be forced away from the cylinder. If, for instance, the pairs of walls 44 and 45 have been selected for engagement with the road, the cylinder 101 will be actuated and the link actuating lever 83 will be operated. The cross bar 95 carried by this link will serve to push the link arms 76 and 81 outwardly and thereby cause the operation of the front wall links 46 and 50. Such movement will cause the walls 45 and 44 to be lowered to their road engaging positions. The amount of movement of these parts and the walls 45 and 44 is controlled by the stop rod 114 and stop nuts 115.

Each front wall link is provided with a spring clip 117 which is preferably secured under the pivot bolt 65. A wall returning spring 120 has its lower end secured to the spring clip 117 and its upper end engaged by the hook of the spring arm 121. This spring arm rests upon the supporting way 41 and has its inner end 122 passing down between the ways 40 and 41 and extended under the way 40. An adjusting screw 123 is carried by each of the spring arms and has its lower end engageable with the upper surface of the way 41 whereby the tension of the wall returning spring may be adjusted, a suitable lock nut being provided for setting the screw in its adjusted position. The wall returning springs 120 serve to return the walls to their normal elevated positions by pulling upwardly on the pivot bolts 65 of the front wall links, the centralizing spring 87 and centralizing arm 79 serving to keep the parts of each of such links in substantially rigid alignment.

The space between the paint walls 42, 43, 44 and 45, respectively, is determined by the position of the hubs 70, 71, 72 and 73 of the front wall links. As hereinbefore pointed out, these hubs, as well as the hubs 84, 90 and 93, respectively, of the link actuating levers 83, 86 and 92 are loosely mounted upon the front link shaft 20, and are held in spaced relation by means of spacers 124 arranged between the respective groups of hubs. If the width of the paint channels formed between either group of walls is to be adjusted, either wider or narrower spacers 124 are put in place. These hubs and spacers are held together upon the shaft 20 in their assembled relation by means of collars 125 fastened in place upon the shaft 20 by suitable set screw means.

Each paint channel formed by the walls 45 and 44, 44 and 43, 43 and 42 is provided, respectively, with a spray nozzle 126, 130 and 131. Each of these spray nozzles is a standard article of manufacture and therefore is not described in detail except to point out that each of them is provided with a paint connection 132, an air spraying connection 133, and a cylinder connection 134 for operating the cylinder of the nozzle which controls the flow of paint, which connections will be hereinafter described. Each of these spray nozzles is suspended centrally within its paint channel between the pairs of walls by means of nozzle arms 135. These arms are pivotally connected to lugs 136 carried by each of the

supporting brackets 104, 105 and 106, whereby each nozzle may be conveniently lifted from its position between the channel for inspection or adjustment. That portion of the nozzle arms immediately in front of the pivotal connection rests upon the supporting ways 40 and 41 and thereby limits the downward movement of the nozzle. Each arm comprises two parts which are tied together by means of a bridging member 137.

The rear wall links 53, 54, 55 and 56 are each provided with a hub 140 which is pivotally mounted upon the rear link shaft 21 and kept in definite spaced relation with each other by means of lock collars 141.

As hereinbefore pointed out, by means of my road marking machine I am able to paint a broken line and to so adjust the machine as to change the length of the line or the cycle thereof. Furthermore, by means of my device I may change at will from a broken line to a solid line. In order to accomplish this I provide distributing units 142, 143 and 144, respectively, for each group of walls and associated paint nozzle.

As shown in Fig. 6, each of these distributing units comprises a casing 145 having a manifold chamber 146 formed in its lower portion, such chamber being connected to a suitable source of valve-controlled air supply (to be hereinafter described) through the inlet connection 159. The casing has screwthreaded thereto a nozzle outlet connection 151 which communicates with a nozzle outlet passageway 152 which is brought into communication with the manifold chamber 146 by means of an outlet valve 153. This valve is carried by a valve rod 154 which is pushed inwardly to unseat the valve at predetermined intervals, as hereinbefore described. A wall outlet passageway 155 is formed in the body of the valve and is brought into communication with the manifold chamber 146 by means of the wall outlet valve 156 which is controlled by means of a valve rod 157 to be hereinafter described. The upper end of the wall outlet passageway 155 is in open communication with an outlet chamber 160 into which a wall outlet connection 161 extends. This wall outlet connection is suitably attached to its associated wall operating cylinder by means to be hereinafter described. The body is provided with an exhaust passageway 162 which is brought into communication with the outlet chamber 160 by means of an exhaust valve 163 which is operated, as hereinbefore described, by means of the valve rod 164. By means of the exhaust valve 163 air contained in the outlet chamber 160 may be exhausted to the atmosphere through the port 162. Valves 153, 155 and 163 are normally urged toward their seats by means of a helical spring 158 mounted upon the rod of each valve.

Arranged at one side of the casing 145 of the distributing unit is a valve arm 165 which is pivotally mounted near its central portion upon a pin 166 carried by the casing. The lower end of this valve carries a roller 170 which is actuated by a cam 180 to be hereinafter described. The lower end of the arm 165 carries adjusting screws 181 and 182 which coact, respectively, with the valve rods 157 and 154. These screws may be adjusted so as to vary the opening of the respective valves 156 and 153. The arm 165 also carries an adjusting screw 183 at a point above its pivotal connection and this screw coacts with the valve rod 164 of the exhaust valve 163 to

operate the same when the arm is in the position shown in Fig. 6. The casing 145 of the distributing unit is also formed in its upper end with a stripe control cylinder 184 which has a piston 185 carrying a piston rod 186. The forward end of the rod extends beyond the casing and is registerable with the upper end of the valve arm 165. An air supply connection 199 is screw-threaded into the casing and serves to conduct air under pressure to the cylinder 184 to cause the rod to move outwardly, thus moving the valve arm to such a position where the roller 170 will be moved out of reach of the cam 189 which is thereby rendered inoperative. The valve arm is maintained normally in the position shown in Fig. 6 by means of a helical spring 191 which has one end secured to the arm and the opposite end to a lug 192 carried by the body 145.

Arranged at the forward end of my device is 20 a cam shaft 193 upon which the cams 189 are mounted, there being one cam for each of the valve arms 165 of the distributing units 142, 143 and 144. Each of these cams is provided with a dwell surface 194 and with an actuating surface 195 of suitable shape to produce the desired actuation of the valve arm 165. Each of these cams is preferably made of two plates 196 each formed with a similar surface contour and each is adjustably mounted upon the cam shaft and locked in place by means of a nut 200 at each end of the shaft whereby the parts may be locked together after adjustment. By means of relative rotation of the two cam parts, the length of the actuating surface 195 may be increased so as to paint a longer line.

The rotation of the cam shaft 193 bears a definite relation to the lineal movement of my device over the pavement and must be rotated with accuracy in order that the cycle of the striping of a broken line may be accurately adjusted and maintained. To accomplish this I provide a driving wheel 201. A sprocket wheel 197 carried by this driving wheel is connected by means of a sprocket chain 202 to a sprocket wheel 203 carried by a gear reduction 204 of any suitable type. The sprocket wheel 203 is connected through the gearing of the gear reduction 204 to the cam shaft 193. Arranged on the side of the device opposite the driving wheel 201 is another wheel 205 which, together with the driving wheel, serves to support the device. Each of these wheels is preferably carried, respectively, by the side plates 17 and 16 in suitable bearings. Each of these wheels is preferably provided with a pneumatic tire and the cycle of a broken line may be varied somewhat by changing the effective diameter thereof by inflation or deflation.

In order to supply air to each of the distributing units I provide an air control valve 206 and a stripe control valve 210. The air control valve is provided with an inlet connection 211 and with an outlet connection 212. It is also provided with an exhaust connection 213. The plug 214 of the valve is rotated by a suitable handle 215 and, in the position shown, the port 216 is in its closed position. The valve is provided with an exhaust port 228 which communicates with the exhaust connection 213 when the valve is in the position shown. When, however, the plug 214 is rotated to open the valve, the passageway 216 will connect the supply pipe 221 coming from any suitable source of air pressure 75

through the connection 211 to the connection 212.

In the drawings, and particularly in Figs. 1 and 5, I have not shown any hose connections between the various parts but, for clearness of illustration, have merely shown lines representing such connections. In Fig. 1 I have shown the air control valve 206 and the stripe control valve 210 as being connected to the distributing unit 144 which is the unit that controls the movement of the walls 42 and 43 through the selective operation of the link actuating lever 92. In Fig. 1, the outlet connection 212 of the air control valve 206 is connected to the inlet connection 150 of the distributing unit 144 by means of a hose line 222. The air pressure connection 133 of the associated nozzle 131 is connected to the nozzle outlet connection 151 by means of a hose line 223. The wall outlet connection 161 of the unit is connected to a branch fitting 224 by means of a hose line 232 by which air under pressure is conducted to the cylinder inlet connection 134 of the nozzle by means of a hose line 225. The fitting 224 is also connected to the connection 113 of the wall cylinder 103 by means of a hose line 226. The fitting 224 is also connected to the exhaust connection 213 of the air control valve 206 by means of a hose line 230. By means of the exhaust connection 213 of the air control valve, the air contained within the hose lines 232, 226 and 225 is exhausted to the atmosphere through the hose line 230 and the exhaust ports 229 and 231 of the valve.

When the machine is to be used for an intermittent or broken line, the air control valve 206 is moved so that air from the air supply line 221 will be conducted from connection 211 through port 216 in the plug of the valve to the connection 212, through hose line 222 to the connection 150 of the distributing unit, thus supplying the manifold chamber 146 with air under pressure. As the device is now drawn across the pavement, the driving wheel 201 will cause the cam shaft 193 to be rotated. As the actuating surface 195 of the cam is brought in contact with the roller 170, the valve arm 165 will be oscillated in clockwise direction as viewed in Figs. 1 and 6 and the exhaust valve 163 will be closed as the wall actuating valve 153 and nozzle valve 151 are opened. Air under pressure will thereby be conducted from the manifold chamber 146 through the wall outlet passageway 155 to the wall outlet connection 161 through the outlet chamber 160. Air will thus pass from the connection 161 through air lines 232 and 225 to the nozzle cylinder inlet connection 134. Air will also pass under pressure from the manifold chamber 146 to the nozzle outlet passageway 152 and thence through outlet nozzle connection 151 and hose line 223 to the nozzle air inlet connection 133 of nozzle 131. When air is supplied to the hose line 225 through the fitting 224 it will also be supplied to the hose line 226 and thereby conducted to the wall cylinder 103 by means of the connection 113, as hereinbefore stated. The operation of this cylinder will cause the link actuating lever 92 to lower the pair of walls 42 and 43 through the medium of the cross bar 96, the link arms 82 and 83, and the front wall links 51 and 52. For clearness, I have described the operation of but one pair of walls and the associated parts for illustrative purposes, and it is obvious that each pair of walls and its paint nozzle has its own distributing unit and control

valves which are operated as just above described.

While I have just described the operation of my device for applying but a single line of paint, it is obvious that where a double broken line is to be applied to the pavement, two adjacent unit groups will be used and the particular air control valves 206 for controlling such groups of units will be operated. It is desirable that the walls be moved to their road engaging positions before paint is sprayed by the nozzles and, to accomplish this, the wall retaining springs are so adjusted in relation to the springs of the nozzles that considerably less pressure is required to operate the coating wall cylinder than to operate the cylinder in the nozzle, whereby the walls are in their road engaging positions before the cylinder of the nozzle is raised to open the paint valve.

When it is desired to paint a solid line for any given distance, the stripe control valve 210 is operated. This valve receives its source of air supply through its inlet connection 233 by a hose line 234, and its outlet connection 235 is connected by means of a hose line 236 to the air supply connection 190 of the stripe control cylinder 184 of the distributing unit 144. The piston of this cylinder will be moved forwardly under the pressure of the air, thereby causing the plunger 186 thereof to oscillate the valve arm 165 to a position where it will open the wall inlet valve 156 and nozzle outlet valve 153 and these valves will thereby be held open irrespective of the position and rotation of the cam 180 as long as the stripe control valve is in its open position. When the end of the solid line has been reached, the stripe control valve is closed and a suitable passageway, shown in dotted lines, will bring the hose line 236 in communication with the exhaust passageway 240 whereby air from the cylinder 184 will be exhausted and the spring 191 will bring the valve arm 165 back to its position where the valves 156 and 153 are closed except in the event that the stripe control valve is closed at such time as the acting surface 195 of the cam is opposite the roller 170, in which event the solid line will continue until the cam has been rotated to the inactive or dwell surface 194. When this condition does occur and it is desired to stop the solid line before the valves can be closed by rotation of the cam, the air control valve 206 is also closed, thereby causing the supply of air to the distributing unit to be cut off and all of the air lines to be exhausted to the atmosphere whereby the spray nozzle will be immediately stopped and the coating walls raised from contact with the pavement. When it is now desired to paint a broken line the cam is again brought into action by opening the air control valve 206, whereby the operation will continue as hereinbefore described. When again starting the broken line, if the cam is not in the proper position to cause the line to register with the place where the broken line should start, the entire painting device may be raised by means of a flexible cable 241, one end of which is connected to the device preferably by being attached to the rear link shaft 21 and the opposite end of which is connected to a lever 242 within reach of an operator. Obviously the pushmobile is moved to the position where it is desired to start the painting and if the painting mechanism of my device is not in proper position of registration the device may be elevated and the driving wheel may be rotated by hand until

the selected cam is in the proper position whereby the device may be lowered onto the pavement and brought into operation by the forward movement of the machine.

In some localities it is desirable to use two colors upon the pavement, used either separately or together, and it is desirable to change quickly from one color to the other without having to rearrange the nozzles, paint or air connections thereto. For this purpose I have provided a two color control valve, shown in Figs. 5, 7, 8 and 9, whereby one distributing unit with its coating parts may be disconnected from the air supply and the air contained in such parts and the connecting hose lines vented to the atmosphere, and at the same time placing the distributing unit handling the other color into service. It is, of course, necessary that a separate distributing valve, a separate wall cylinder, and a separate nozzle be provided for each color and each paint channel.

In Fig. 5, which is largely diagrammatic, I show a valve 243 and two separate distributing units 244 and 245, one for each of the two colors for which the apparatus of Fig. 5 is designed. The distributing units 244 and 245 control, respectively, spray nozzles 246 and 250. These distributing units are of the same design as the distributing unit 145 shown in detail in Fig. 6. In Fig. 5, for convenience of illustration, I have omitted the showing of the walls but have shown one link actuating lever 253 in fragmentary manner. This lever is provided with a pad 254 which extends across the plungers 255 and 256 of the two wall cylinders 251 and 252, respectively, provided one for each color.

The control valve for use with a two color machine comprises preferably a stator part 260 and a rotor part 261. The stator part 260 is provided with an enlarged base 262 which is stationarily arranged in suitable position and within easy control of an operator of the pushmobile shown in Fig. 10 or the truck shown in Fig. 11. The rotor 261 is provided with a tapered bore which fits over the plug portion 263 of the stator member. The joint between these two parts is of course close fitting so as to seal the valve. The plug of the stator is provided with a centrally arranged inlet passageway 264 which extends from the upper end thereof down into the plug a considerable distance, the upper end of the passageway being screwthreaded for the reception of an air supply connection 265. The bottom of this passageway 264 terminates at a lateral passageway 266 extending outwardly to the surface of the plug. The stator is provided with ports 270 and 271 which are arranged at an angle with each other and registerable with the lateral port 266 by rotation of the rotor member 261. A suitable handle 272 is provided upon the stator whereby the same may be manipulated. Connected to the ports 270 and 271 are outlet connections 273 and 274, respectively, which are suitably connected to the various parts of the structure as hereinafter described.

The stator member is provided in its base 262 with screwthreaded exhaust connections 275 and 276. Passageways 280 and 281 extend upwardly from each of the connections 275 and 276, respectively, and terminate at their upper ends in lateral passageways 282 and 283. These passageways are converged toward each other somewhat, as shown in Fig. 8, and the rotor part 261 of the valve is provided with an arcuate slot 284 which exposes both of the passageways 282 and 283

when the valve is in neutral position, as shown in the drawings. Two pairs of stop surfaces 285 and 286 may be provided on the rotor and stator parts 261 and 260 if desired for limiting the rotative movement to a predetermined amount.

As hereinbefore stated, a separate distributing unit must be used for each color paint nozzle employed and, for convenience of illustration, I have shown two nozzles in Fig. 5. Therefore, two associated distributing units 244 and 245 are shown. Since white and yellow are colors usually used in road striping, I will refer to the distributing unit 244 and its associated nozzle 246 as having to do with, for instance, the white color and the distributing unit 245 and associated nozzle 246 as having to do with the other color, for instance, the yellow. As shown in Fig. 5, the inlet connection 299 of the distributing unit 244 controlling the white paint is connected to the connection 273 of the valve by means of a hose line 291, and the supply connection 292 of the distributing unit 245, controlling the yellow paint, is likewise connected to the connector 274 of the valve by means of a hose line 293. Air is supplied to the valve through the connection 265 by means of a supply line 294. Thus by rotating the rotor 261 of the valve, air may be supplied to either the distributing unit 244 or the distributing unit 245. When the air is changed from one distributing unit to the other through the connections 273 and 274, the distributing unit which is cut off will be exhausted to the atmosphere through the valve and connections as hereinafter described. The exhaust connection 276 of the valve is connected to the wall outlet connection 295 of the unit 244 by means of a pipe line 296, and the exhaust connection 275 of the valve is connected to the wall inlet connection 300 of the unit 245 by means of a pipe line 301.

As hereinbefore pointed out, I provide spray nozzles 246 and 259 and wall actuating cylinders 251 and 252 for each of the distributing units 244 and 245, respectively, which are controlled by the two color control valve and cam mechanism of the units. The cylinder connection 302 of the nozzle 246 is connected to a branch connection 303 in the air line 296 by means of an air line 304, and the wall actuating cylinder 251 is also connected to the branch fitting 303 by means of an air line 305. In similar manner, the air inlet connection 306 of the nozzle 246 is connected to the nozzle outlet connection 310 of the distributing unit 244 by means of a pipe line 311. In similar manner, the air cylinder connection 312 of the nozzle 259 is connected to the branch connection 313 in the air line 304 by means of a hose line 314. The nozzle outlet connection 315 of the distributing unit 245 is connected to the air nozzle connection 316 of the nozzle 259 by means of a hose line 320. The wall cylinder 252 is connected to the branch fitting 313 by means of a hose line 321.

Where two or more nozzles are employed, each handling a different color, as just above described, it is necessary to provide a stripe control valve 322 for temporarily discontinuing the automatic cam action upon the valves of either distributing unit. This valve is similar in function to the stripe control valve 210 and it receives its supply of air from the main air supply line 323 through a branch pipe 324. The outlet line 325 from this valve is connected to the air supply connection 326 of the unit 244 by means of a hose line 320. The air supply connection 321 of the distributing unit 245 is connected by means

of a hose line 322 to a branch connection 323 in the outlet line 325. If desired, one of the valves 322 may be provided for each of the distributing units, but one valve is sufficient since the actuation of the stripe control cylinder in either of the distributing units will not become effective unless that distributing unit has been supplied with air under pressure through the two-color control valve 243. The valve 322 is provided with a vent 324 whereby air in either of the lines 320 or 322, and their connected stripe control cylinders will be exhausted to the atmosphere when the supply of air to such cylinders is cut off by this valve.

With the parts of the device shown and described in connection with Fig. 5, all of the air in the air cylinders is exhausted and there is no pressure in any of the lines. When, for instance, it is desired to spray white paint through the nozzle 246, the two-color control valve 243 will be operated so as to bring the lateral passageway 266 in registration with the outlet fitting 273 whereby air from the supply 323 will pass through air line 294 to the inlet connection 299. Air will thus pass through the hose line 291 to the inlet connection 299, thereby supplying air to the distributing unit 244, in a manner similar to the supply of air to the distributing unit 245, hereinbefore described. If an intermittent or broken line is to be placed upon the pavement, the stripe control cylinder 297 and 298 of each distributing unit 244 and 245, respectively, will be inactive and the cams 180 will cause the cam arms 325 of both distributing units to be oscillated. Since air is being supplied to the wall outlet cylinder 251 through the hose line 305 and branch fitting 303, the wall cylinder will operate the link actuating lever 253, thereby causing the walls controlled thereby to be lowered to form the paint channel. Simultaneously with the lowering of the walls, the cylinder of the nozzle 246 will be elevated, thus opening the paint supply coming through hose line 336 which is connected to the paint inlet 341 of the nozzle. Air to spray the paint will also be conducted through the hose line 311 to the inlet 306 of this nozzle. As soon as the surface or dwell 194 of the cam is opposite the roller of the arm 335 the air to the various cylinders and the nozzle will be shut off and the vent 320 will allow air contained in all of these various hose lines and connected parts to be vented to the atmosphere through the operation of the vent valve (not shown) in the unit. Obviously, as described in connection with the control unit 145 of the other form of device, when it is desired to paint a solid line of the color just described, the two-color control valve 243 will be allowed to remain in the position to which it has been operated and the stripe control valve 322 actuated to allow air under pressure to pass to the stripe control cylinder 297 of the distributing unit 244 whereby the arm 335 of this unit will be held in such position to allow air to pass uninterrupted to the wall cylinder 251 and to the spray nozzle 246. During the time the outlet connection 273 is in communication with the air supply, the exhaust ports 281 and 283 have been closed by the rotation of the valve rotor member 261 and air therefor contained in the hose line 296 will not be exhausted. However, any air which has been contained in the line 304 by reason of a previous operation of the distributing unit 245 and associated parts will be exhausted to the atmosphere for the reason that the exhaust ports 280 and 282 of the

valve are open to the atmosphere by and through the arcuate slot 234.

When it is now desired to change from one color to the other, the rotor member 261 of the two-color control valve is moved so as to bring the outlet 274 in communication with the inlet passages 264 and 266 and air will thus be conducted through the hose line 293 to the distributing unit 245, thus placing this distributing unit under pressure and ready to distribute air to the various associated parts. Obviously, when the two-color control valve is moved to the position where it energizes the distributing unit 245, the distributing unit 244 is cut off and the air contained in this unit and its associated parts will be exhausted to the atmosphere through exhaust passageways 281 and 283. The air in distributing unit 245 is now supplied to the various co-acting parts of the device as just described in connection with the operation of the distributing unit 244, thereby energizing the wall cylinder 252 and the nozzle 250, thereby allowing paint to flow through the hose 337 to this nozzle through the paint inlet 341 of this valve. With the distributing valve 245 energized, the wall cylinder 252 and nozzle 250 will be actuated in periodic manner except in the case where a solid line is desired when the valve 322 will be actuated to produce the results described in connection with the operation of the distributing unit 244. This unit 245 is provided with a vent 342 which acts in a manner similar to the vent 340 of the unit 244 to vent the cylinders and air lines when the line is interrupted by the rotation of the cam.

While I have described the operation of a single group of two-color parts for but one paint channel, it is to be understood that each paint channel of the device is also provided with a separate group of parts.

My device is of such a nature that it may be placed upon a pushmobile like that shown in Fig. 10. Such a pushmobile comprises a chassis 343 having rear supporting wheels 344 at its rear end and front supporting wheels 345 at its forward end for steering the vehicle. The front wheels are controlled by a steering arm 346 within easy reach of an operator of the pushmobile. A steering boom 350 is carried at the forward end to guide the steering of the device along a predetermined path. An operator sits upon a seat 351 and in front of him is a support 352 on which is mounted either the air control valve 206 of Fig. 1 or the two-color air control valve 243 of Fig. 5. Either of the stripe-control valves 210 or 322 are also mounted within easy reach of the operator. Obviously the paint and air are supplied from a suitable source carried by the truck which pushes the pushmobile and which is conducted to the pushmobile through the air line 353 and through the paint line 354.

In Fig. 11, as hereinbefore pointed out, I have shown my device attached to the rear of a truck 355. As is customary, a suitable platform or support 356 is attached to the rear of the truck and carries a control standard 369. The control standard has means for carrying the valves 206 and 210 or valves 243 and 322 and also carries the bracket 35 and a ball stem 33, as hereinbefore described.

Obviously, some modifications of my device as shown and described may be made without departing from the spirit of my invention or the scope of the appended claims, and I do not, therefore, wish to be limited to the exact embodiment herein shown and described, the de-

vice shown being merely the preferred embodiment of the invention.

Having thus described my invention, what I claim is:

- 5 1. A road marking machine comprising a frame, a plurality of walls spaced to define paint channels therebetween, paint applying means carried by said frame and arranged between each two adjacent walls, rear wall links and front wall links pivotally connected to said walls, the free end of each of said rear wall links being mounted upon a rear wall shaft, the free end of each of said front wall links being pivotally mounted upon a front link shaft, said rear and front link shafts being supported by said frame, a link actuating lever pivotally carried by said front wall shaft and mounted between the front links of each pair of paint walls, means carried by each lever for actuating one pair of adjacent walls, and means for selectively moving said link actuating levers.
- 10 2. A road marking machine comprising a frame, a plurality of walls spaced to define paint channels therebetween, paint applying means carried by said frame and arranged between each two adjacent walls, rear wall links and front wall links pivotally connected to said walls, the free end of each of said rear wall links being pivotally mounted upon a rear wall shaft, the free end of each of said front wall links being pivotally mounted upon a front link shaft, said rear and front link shafts being supported by said frame, a link actuating lever pivotally carried by said front link shaft and mounted between the front links of each pair of paint walls, means carried by each lever for actuating one pair of adjacent walls, and means for selectively operating any number of said actuating levers and their associated paint applying means in timed relation to each other.
- 15 3. A road marking machine comprising a frame, a plurality of walls spaced to define paint channels therebetween, paint applying means arranged between each two adjacent walls, links for pivotally connecting said paint walls to said frame, actuating means for selectively operating any desired number of pairs of walls to move them to road engaging positions, means for returning said walls to their elevated positions, distributing units for controlling the wall actuating means and the paint applying means, and means for selectively operating the distributing units.
- 20 4. A road marking machine comprising a frame, a plurality of walls spaced to define paint channels therebetween, pneumatically operated paint applying means arranged between each two adjacent walls, links for pivotally connecting said paint walls to said frame, actuating means for selectively operating any desired number of pairs of walls to move them to road engaging positions, means for returning said walls to their elevated positions, pneumatic means for controlling said wall actuating means, distributing units for controlling said pneumatic means and said pneumatically operated means, a control valve for supplying air to each of the distributing units, and means for operating said distributing units.
- 25 5. A road marking machine comprising a frame, a plurality of walls spaced to define paint channels therebetween, pneumatically operated paint applying means arranged between each two adjacent walls, links for pivotally connecting said paint walls to said frame, actuating means for selectively operating any desired number of pairs of walls to move them to road engaging positions, means for returning said walls to their elevated

positions, pneumatic means for controlling said wall actuating means, distributing units for controlling said pneumatic means and said pneumatically operated means, a control valve for supplying air from a suitable source to each distributing unit, an actuating cam for each distributing unit, and means contacting with the surface of the road for causing the cams to be operated, whereby a number of broken lines of predetermined cycle may be applied to the road.

6. A road marking machine comprising a frame, a plurality of walls spaced to define paint channels therebetween, pneumatically operated paint applying means arranged between each two adjacent walls, links for pivotally connecting said paint walls to said frame, actuating means for selectively operating any desired number of pairs of walls to move them to road engaging positions, means for returning said walls to their elevated positions, pneumatic means for controlling said wall actuating means, distributing units for controlling said pneumatic means and said pneumatically operated means, a control valve for supplying air from a suitable source to each distributing unit, an actuating cam for each distributing unit, means contacting with the surface of the road for causing the cams to be operated, and means for temporarily interrupting the action of the actuating cams, whereby a solid line of desired length may be applied to the road.

7. A road marking machine comprising a frame, a plurality of walls spaced to define paint channels therebetween, pneumatically operated paint applying means arranged between each two adjacent walls, links for pivotally connecting said paint walls to said frame, actuating means for selectively operating any desired number of pairs of walls to move them to road engaging positions, means for returning said walls to their elevated positions, pneumatic means for controlling said wall actuating means, distributing units for controlling said pneumatic means and said pneumatically operated means, a control valve for supplying air from a suitable source to each distributing unit, an actuating cam for each distributing unit, means contacting with the surface of the road for causing the cams to be operated, a stripe control cylinder carried by each distributing unit, and a stripe control valve for governing the operation of said cylinder, whereby the action of the actuating cams may be temporarily interrupted.

8. A road marking machine comprising a frame, a plurality of walls spaced to define paint channels therebetween, pneumatically operated paint applying means arranged between each two adjacent walls, front and rear wall links pivotally connected to said walls for movably suspending the same to maintain substantial parallel relationship with the surface of the road, the free end of said front and rear wall links being pivotally carried by said frame, each of said front wall links having a link arm, a link actuating lever arranged between each pair of front links, each of said levers being pivotally carried by the frame, a cross bar carried by each lever for coaction with the adjacent link arm on each side of said lever for selecting the desired pair of walls, pneumatic means for controlling the operation of each of said actuating levers, and means for controlling said pneumatic means.

9. A road marking machine comprising a frame, a plurality of walls spaced to define paint channels therebetween, pneumatically operated paint applying means arranged between each two

adjacent walls, front and rear wall links pivotally connected to said walls for movably suspending the same to maintain substantial parallel relationship with the surface of the road, the free end of said front and rear wall links being pivotally carried by said frame, each of said front wall links having a link arm, a link actuating lever arranged between each pair of front links, each of said levers being pivotally carried by the frame, a cross bar carried by each lever for coaction with the adjacent link arm on each side of said lever for selecting the desired pair of walls, pneumatic means for controlling the operation of each of said actuating levers, operating means for controlling said pneumatic means and said paint means in timed relation, and means for automatically and periodically interrupting said operating means, whereby a broken line will be applied to the road.

10. A road marking machine comprising a frame, a plurality of walls spaced to define paint channels therebetween, pneumatically operated paint applying means arranged between each two adjacent walls, front and rear wall links pivotally connected to said walls for movably suspending the same to maintain substantial parallel relationship with the surface of the road, the free end of said front and rear wall links being pivotally carried by said frame, each of said front wall links having a link arm, a link actuating lever arranged between each pair of front links, each of said levers being pivotally carried by the frame, a cross bar carried by each lever for coaction with the adjacent link arm on each side of said lever for selecting the desired pair of walls, pneumatic means for controlling the operation of each of said actuating levers, operating means for controlling said pneumatic means and said paint means in timed relation, means for automatically and periodically interrupting said operating means, and manually controlled means for temporarily rendering said automatic means inoperative, whereby an unbroken line will be applied to the road.

11. A road marking machine comprising a frame, a plurality of walls spaced to define paint channels therebetween, pneumatically operated paint applying means arranged between each two adjacent walls, front and rear wall links pivotally connected to said walls for movably suspending the same to maintain substantial parallel relationship with the surface of the road, the free ends of said rear wall links being pivotally mounted upon a rear wall shaft and the free ends of said front wall links being pivotally mounted upon a front wall shaft, each of said front wall links having an upstanding link arm, a link actuating lever pivotally mounted upon the front link shaft between each pair of front wall links, a cross bar carried by each lever for coaction with the adjacent link arm on each side of said lever for selecting the desired pair of walls, pneumatic means for controlling the operation of each of said actuating levers, a distributing unit for each pair of walls, a control valve for selectively supplying air under pressure to either distributing unit, and means for actuating said distributing unit.

12. A road marking machine comprising a frame, a plurality of walls for defining paint channels therebetween, a pneumatically operated paint nozzle arranged between each two adjacent walls, links for pivotally connecting said paint walls to said frame, actuating means for selectively operating any desired number of pairs

of walls to move them to road engaging positions, means for returning said walls to their inoperative positions, pneumatic means for controlling said wall actuating means, a distributing unit for each of said wall actuating means and said paint nozzle, comprising a wall outlet valve and a nozzle outlet valve for distributing air under pressure to the wall actuating pneumatic means and the nozzle actuating pneumatic means, and an exhaust valve, cam means for periodically closing said exhaust valve and opening said wall actuating valve and said nozzle valve to cause air to flow to the wall actuating means and paint actuating means, and means for actuating said cam in timed relation with the movement of the machine.

13. A road marking machine comprising a frame, a plurality of walls for defining paint channels therebetween, a pneumatically operated paint nozzle arranged between each two adjacent walls, links for pivotally connecting said paint walls to said frame, actuating means for selectively operating any desired number of pairs of walls to move them to road engaging positions, means for returning said walls to their inoperative positions, pneumatic means for controlling said wall actuating means, a distributing unit for each of said wall actuating means and said paint nozzle, comprising a wall outlet valve and a nozzle outlet valve for distributing air under pressure to the wall actuating pneumatic means and the nozzle actuating pneumatic means, an exhaust valve, cam means for periodically closing said exhaust valve and opening said wall actuating valve and said nozzle valve to cause air to flow to the wall actuating means and paint actuating means, means for actuating said cam in timed relation with the movement of the machine, a stripe control cylinder, and a control valve connecting the source of air under pressure to said cylinder to temporarily interrupt the action of the cam for holding the wall outlet valve and the nozzle outlet valve open, whereby a continuous line will be applied to the road.

14. A road marking machine comprising a frame, a pair of walls movably supported by said frame for defining a paint channel, a plurality of paint applying devices mounted between said walls for applying different colored paints, a distributing unit for each paint applying device, a wall cylinder controlled by each distributing unit for moving said walls into operative relation with the surface of the road, means connecting each distributing unit with its associated paint applying device, and an air control valve, said valve being provided with separate means for connecting a source of air to each distributing unit and also being formed with an exhaust passageway for each distributing unit, whereby when air is supplied to the distributing unit for applying one color through the associated paint applying device, air in the other distributing unit and its associated parts will be exhausted to the atmosphere.

15. A road marking machine comprising a frame, a pair of walls movably supported by said frame for defining a paint channel, a plurality of paint applying devices mounted between said walls for applying different colored paints, a distributing unit for each paint applying device, a wall cylinder controlled by each distributing unit for moving said walls into operative relation with the surface of the road, means connecting each distributing unit with its associated paint applying device, and an air control valve, comprising a

5 stator part and a rotor part, said stator part being formed with a centrally arranged inlet passageway and said rotor part being formed with spaced, registerable outlet ports for connection one to each of said distributing units, said stator part having exhaust passageways opening into a slot formed in the stator, each of said exhaust passageways being connected to one of said distributing units, the slot of said stator being so 10 proportioned and positioned that when air is supplied to one of the distributing units, the exhaust passageway connected to that particular unit will be closed.

16. A road marking machine comprising a frame, a pair of walls movably supported by said frame for defining a paint channel, a plurality of paint applying devices mounted between said walls for applying different colored paints, a distributing unit for each paint applying device, a wall cylinder controlled by each distributing unit for moving said walls into operative relation with the surface of the road, means connecting each distributing unit with its associated paint applying device, cam means for intermittently supplying air through either distributing unit to the associated paint applying device and wall actuating cylinder, and an air control valve, said valve being provided with separate means for connecting a source of air to each distributing unit and also being formed with an exhaust passageway for each distributing unit, whereby when air is supplied to the distributing unit for applying one color through the associated paint applying device, air in the other distributing unit and its associated parts will be exhausted to the atmosphere.

17. A road marking machine comprising a frame, a pair of walls movably supported by said frame for defining a paint channel, a plurality of paint applying devices mounted between said walls for applying different colored paints, a distributing unit for each paint applying device, means controlled by each distributing unit for moving said walls into operative relation with the surface of the road, means connecting each distributing unit with its associated paint applying device, and an air control valve, said valve being provided with separate means for connecting a source of air to each distributing unit and also being formed with an exhaust passageway for each distributing unit, whereby when air is supplied to the distributing unit for applying one color through the associated paint applying device, air in the other distributing unit and its associated parts will be exhausted to the atmosphere.

18. A road marking machine comprising a frame, a pair of walls movably supported by said frame for defining a paint channel, a plurality of paint applying devices mounted between said walls for applying different colored paints, a distributing unit for each paint applying device, means controlled by each distributing unit for moving said walls into operative relation with the surface of the road, means connecting each distributing unit with its associated paint applying device, and an air control valve, comprising a stator part and a rotor part, said stator part being formed with a centrally arranged inlet passageway and said rotor part being formed with spaced, registerable outlet ports for connection one to each of said distributing units, said stator part having exhaust passageways opening into a slot formed in the stator, each of said exhaust passageways being connected to one

of said distributing units, the slot of said stator being so proportioned and positioned that when air is supplied to one of the distributing units, the exhaust passageway connected to that particular unit will be closed.

19. A road marking machine comprising a frame, a pair of walls movably supported by said frame for defining a paint channel, a plurality of paint applying devices mounted between said walls for applying different colored paints, a distributing unit for each paint applying device, a wall cylinder controlled by each distributing unit for moving said walls into operative relation with the surface of the road, means connecting each distributing unit with its associated paint applying device, cam means for intermittently supplying air through either distributing unit to the associated paint applying device and wall actuating cylinder, a stripe control cylinder carried by each distributing unit, stripe control valve means for connecting a source of air supply to said stripe control cylinders to temporarily interrupt the action of the cam means, and an air control valve, said valve being provided with separate means for connecting a source of air to each distributing unit and also being formed with an exhaust passageway for each distributing unit, whereby when air is supplied to the distributing unit for applying one color through the associated paint applying device, air in the other distributing unit and its associated parts will be exhausted to the atmosphere.

20. A road marking machine including walls spaced to define a paint channel therebetween, paint applying means arranged between said walls, front and rear wall links pivotally attached to the ends of said walls for movably suspending the same in substantially parallel relationship to the surface of the road, means for normally holding said walls in elevated positions, means for moving said walls to road engaging positions, each of said front wall links comprising an operating part pivotally attached to the machine and a free part pivotally attached to the wall, a link pivot uniting said parts so as to permit relative rotative movement thereof, and centralizing means for resiliently holding said parts in yieldable alignment, whereby said walls are free to float and will tilt to any position necessary when passing over a foreign object.

21. A road marking machine including walls spaced to define a paint channel therebetween, paint applying means arranged between said walls, front and rear wall links pivotally attached to the ends of said walls for movably suspending the same in substantially parallel relationship to the surface of the road, means for normally holding said walls in elevated positions, means for moving said walls to road engaging positions, each of said front wall links comprising an operating part pivotally attached to the machine and a free part pivotally attached to the wall, a link pivot uniting said parts so as to permit relative rotative movement thereof, a centralizing arm carried by each of said free parts, and a centralizing spring for keeping said parts in yieldable alignment whereby said walls are free to float and will tilt to any position necessary when passing over a foreign object.

22. A road marking machine comprising a frame, a plurality of walls spaced to define a paint channel therebetween and arranged to be moved in pairs, paint applying means carried by said frame and arranged between each two adjacent walls, a rear wall shaft, a front wall shaft,

said shafts being carried by said frame, rear wall links and front wall links pivotally connected to said walls, the free end of each of said rear wall links being pivotally mounted upon said rear wall shaft, the free end of each of said front wall links being pivotally mounted upon said front link shaft, and means carried by said front link shaft for selectively moving any number of pairs of adjacent walls.

23. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, means for normally holding said walls in their elevated positions for independent movement, and independently actuated means for selecting and moving any two adjacent walls as a pair to road engaging positions.

24. A road marking machine including paint confining walls spaced to define a paint channel therebetween, paint applying means arranged between said walls, a link pivotally connected to each end of each wall for movably suspending said walls in substantially parallel relationship to the surface of the road, means engageable with one of said links for normally holding said walls in their elevated positions, means engageable with one of the links of each wall for moving said walls to road engaging positions, and means associated with one of said links of each wall and operable independently of the wall moving means for permitting said wall to move upwardly from road engaging position independently of the wall moving means.

25. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, means for normally holding said walls in their elevated positions for independent movement, normally stationary paint applying means arranged between each pair of walls, operating means for said paint applying means, and manually actuated unit means for controlling said independently actuated means and said operating means in timed relation with each other.

26. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, means for normally holding said walls in their elevated positions for independent movement, means for operating said paint applying means, and independently actuated means for selecting and moving any two adjacent walls as a pair to road engag-

ing positions in sequential relation to said paint applying means.

27. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, pneumatic actuating means for moving said walls to road engaging positions, pneumatic operating means for said paint applying means, said operating means being supplied with fluid under pressure from the same source and working at a pressure higher than said actuating means, whereby the selected pair of walls will be moved before said paint applying means is operated, and manually actuated unit means for controlling said actuating means and said operating means.

28. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, pneumatic actuating means for moving said walls to road engaging positions, pneumatic operating means for said paint applying means, said operating means being supplied with fluid under pressure from the same source and working at a pressure higher than said actuating means, whereby the selected pair of walls will be moved before said paint applying means is operated, and a control valve for actuating said last two mentioned pneumatic means.

29. A road marking machine including paint confining walls interspaced to define a paint channel therebetween, means for pivotally suspending each end of each of said walls independently of the other walls and for independent vertical movement to road engaging and elevated positions, normally stationary paint applying means arranged between said walls, means for normally holding said walls in their elevated positions, automatic means for periodically moving and holding said walls to and in road engaging positions when paint is to be intermittently applied to the surface of the road in the channel defined by the walls, and means associated with said suspending means for permitting individual upward movement of said walls from road engaging positions independently of said moving and holding means.

30. A road marking machine including paint confining walls interspaced to define a paint channel therebetween, means for pivotally suspending each end of each of said walls independently of the other walls and for independent vertical movement to road engaging and elevated positions, normally stationary paint applying means arranged between said walls, means for normally holding said walls in their elevated positions, actuating means for moving and holding said walls to and in road engaging positions and for opening said paint applying means after

said walls have reached such positions, automatic means for controlling the operation of said actuating means at predetermined spaced intervals of time, and means associated with said suspending means for permitting upward movement of said walls from road engaging positions independently of said moving and holding means.

31. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, and means for selectively moving said walls in pairs.

32. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, and means for selectively moving said walls in pairs.

33. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, and pneumatically operated means for selectively moving the desired number of pairs of walls and for opening their associated paint applying means, said operating means being supplied with fluid under pressure from the same source and working at a lower fluid pressure than that of said paint applying means, whereby said walls will be moved into road engaging positions before said paint applying means is operated.

34. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, and pneumatically operated means for selectively moving the desired number of pairs of walls and for opening their associated paint applying means, said operating means being supplied with fluid under pressure from the same source and working at a lower fluid pressure than that of said paint applying means, whereby said walls will be moved into road engaging positions before said paint applying means is operated, and valve

means for energizing the selected pneumatically operated means.

35. A road marking machine including a plurality of paint confining walls arranged adjacent each other and interspaced to define paint channels therebetween, means for pivotally suspending each end of each of said walls so as to maintain the lower edge thereof in substantially parallel relationship with the surface of the road, each of said walls being independently suspended so as to be capable of movement in pairs, normally stationary paint applying means arranged between each two adjacent walls, means for normally holding said walls in their elevated positions for independent movement, independently actuated means for selecting and moving any two adjacent walls as a pair to road engaging positions in timed relation to and before the flow of paint through said paint applying means, and stop means associated with said actuating means for limiting the downward movement of said walls.

36. A road marking machine comprising a frame, a plurality of walls spaced to define paint channels therebetween and arranged to be actu-

ated in pairs, paint applying means arranged between each two adjacent walls, front and rear wall links pivotally carried by said frame and pivotally connected to said walls for movably suspending the same, selective actuating means associated with said front wall links for selecting and moving any number of pairs of walls, and means for operating said actuating means.

37. A road marking machine comprising a frame, a plurality of walls spaced to define paint channels therebetween and arranged to be actuated in pairs, paint applying means arranged between each two adjacent walls, front and rear wall links pivotally carried by said frame and pivotally connected to said walls for movably suspending the same, selective actuating means associated with said front wall links for selecting and moving any number of pairs of walls, means for operating said actuating means, and a distributing unit for separately and sequentially controlling the operating of each actuating means and each associated paint applying means, whereby the selected walls are moved to road engaging positions before the paint is applied.
